STORAGE RACK

Filed Nov. 13, 1926

UNITED STATES PATENT OFFICE.

LEE L. McGOOGAN, OF ST. PAULS, NORTH CAROLINA.

STORAGE RACK.

Application filed November 13, 1926. Serial No. 148,251.

My invention relates to means for storing the side rails of beds in furniture stores and other places. Heretofore, it has been customary for operators of furniture stores, 5 when receiving a shipment of beds, to store the side rails of the beds by piling the same on the floor, thus making it very difficult to find the desired side rails for any particular bed.

10 An object of my invention is to provide a knock-down rack in which bed rails may be stored in a furniture store and other places in assorted lots.

Another object of my invention is to provide 15 a storage rack for bed rails, piping, and other straight objects, which rack is capable of being folded up and stored in a small place when not needed.

Having thus stated some of the objects of 20 my invention, other objects will appear as the description proceeds.

In the drawings, I have shown a preferred embodiment of my invention, in which—

Figure 1 is a front elevation of my storage rack;

Figure 2 is an end view of my storage rack, looking in the direction indicated by the arrow A in Figure 1;

Figure 3 is an enlarged detailed view of 25 the sliding means located on the connecting rail;

Figure 4 is a cross sectional view taken along the lines 4—4 in Figure 3;

Figure 5 is an enlarged detailed view 30 showing the pivotal connection between the connecting rail and the frame C.

A brief description of the drawings, having 40 been given, a detailed description of the same will now follow, in which like reference characters indicate corresponding parts throughout the drawings.

The letters B and C indicate two similar frames, each of which has the bases 10 and 45 11 secured thereto. The main frame 12 of these frames B and C is preferably made of tubular material and is U-shaped in form and running from one upright portion to the other, are the pieces of tubular material 13, which penetrates the side walls of the 50 tubular member 12 and are secured in place by welding, or any other suitable means. These tubular members 13 are preferably flattened and stand on the edges. Piercing the central portion of the rearmost portion 55 of the members 12 are the bolts 14, which have a nut 15 threadedly engaging one end,

and the other end 16 of the bolts 15 have enlarged flattened portions which have two vertical holes therethrough, for the reception of the pins 17 and 18. The connecting rail 60 19 is forked and has the portions 20 and 21 fitting against the upper and lower surface of the portion 16. The portions 20 and 21 have vertical holes therethrough, which register with the vertical holes in the portion 65 16, through which the pins 17 and 18 are adapted to be fitted.

Slidably mounted on the connecting rail 19 is the member 22, which is composed of the members 23 and 24, which members are 70 secured to each other around the connecting rail by means of the bolts or rivets 25, 26, 27, 28. A plurality of perforations 29, 30, 31, 32, 33, 34, 35, and 36 occur along the upper and lower edges of the member 22. These 75 are adapted to have the rods or chains 37, 38, 39, and 40 secured therein, the other ends of the said rods or chains being secured to the eye-bolts 41, 42, 43, and 44, which eye-bolts penetrate the tubular members 12, and 80 have nuts 45, 46, 47, and 48 on their respective ends.

It will thus be seen that by means of the holes 29 to 36, the eye-bolts 42 to 44, and the rods 37 to 40 and the connecting rail 19, the 85 frames B and C may be adjustably and rigidly secured together by inserting the forked ends of the rods 37 to 40 in any set of the holes 29 to 36 and then tightening the nuts 45 to 48. By removing either of the pins 90 17 and 18 at each end of the connecting rail, the other pin will serve as a pivot for the frames B and C, and the same may be spread apart for more easily placing the rails on the tubular members 13 for storage, or for 95 removing the rails from the storage rack. When it is desired to store this rack, the members B and C may be folded toward each other by removing one of the pins 17 or 18, and removing the ends of the rods or chains 37 to 40 from the holes in the member 22. When it is desired to ship this rack, it is readily apparent that the same may be quickly dismantled for packing and shipping.

105 In the description, I have set forth a preferred embodiment of my invention, and although specific terms are employed, they are used in a generic and descriptive sense, and not for purposes of limitation, the scope 110 of the invention being set forth in the appended claims.

I claim:

1. In a device of the kind described, two inverted **U**-shaped frames disposed apart from each other and in parallel relation, 5 horizontally disposed rods running from the leg of each frame to the other leg of the frame, a rod connecting the leg of one frame to the corresponding leg of the other frame, a pivotal connection between the said rod 10 and the said frames, means for optionally locking said pivotal connection, a member mounted on the medial portion of the said rod, holes in the said member, braces connected to the said member and to the upper 15 and lower portions of the legs of the **U**-shaped frames, and means for adjusting the tautness of the said braces.

2. In a device for storing and displaying bed rails and similar articles, two vertically 20 positioned parallel spaced racks, said racks being inverted **U**-shaped in contour, the rear medial portions of each rack being pivotally secured to a connecting rod running between the racks, a member on the medial portion 25 of the connecting rod, braces secured to the said member and running to the upper and lower portions of the rear portion of the **U**-shaped frames, and adjustable means for securing the braces to the said **U**-shaped 30 frames.

3. In a device for storing bed rails and other objects, two parallel racks spaced apart from each other, a rod having forked ends connecting the rear medial portions of the

racks to each other, a pivotal connection 35 between the rod and the racks, said pivotal connection comprising a member secured to the rack and being adapted to fit into the forked ends of the rod, two vertically disposed intermeshing holes in the forked ends 40 of the rod and in the members secured to the racks, a pin adapted to be inserted in one of the holes to act as a pivot, and a second removable pin adapted to be inserted in the other hole to lock the racks in parallel 45 relation to each other.

4. In a display rack, two inverted **U**-shaped rack members spaced apart from each other and in parallel relation to each other normally, a rod running from the rear portion of one of the rack members to the rear portion of the other rack member, pivotal connections between the rod and the rack members to allow the front portions of the rack members to be swung toward and away 50 from each other, means associated with the racks and the rod for locking the racks in position to prevent swinging of the same, a member on the medial portion of the rod, holes in the member adapted to receive one 55 end of a rod, members secured to the racks adapted to receive the other end of the said second rod, the means associated with the rack to receive the end of the said second rod being adjustable with relation to the 60 65 rack.

In testimony whereof I affix my signature.
LEE L. McGOOGAN.
